MOP

Filed Nov. 26, 1928

Fig. 3.

Harry Hertzberg INVENTOR

BY Martin Joachimson
ATTORNEY

UNITED STATES PATENT OFFICE

HARRY HERTZBERG, OF BROOKLYN, NEW YORK

MOP

Application filed November 26, 1928. Serial No. 321,923.

This invention relates to improvements in mops and more particularly to that type of such devices in which the mop swatch is carried by a sheath of fabric and is supported 5 on a skeleton frame from which it may be removed for cleaning or other purposes.

It is a particular object of this invention to provide a mop frame which is so attached to its holder that it may be easily and quickly detached therefrom.

It is another object of the invention to provide a mop holder and rotatable frame which are in frictional engagement with each other to hold the mop stationary at different 15 angles with its holder, and to arrest it in one fixed position.

It is a further object of the invention to provide a mop frame which comprises a fully 20 closed loop for the support of the swatch so that objects may not be pressed in between the open space of the frame, be caught therein, and distort the swatch and also to permit a quick detachment of the swatch from its frame.

25 With these and other objects in view which will become clearer as the description progresses, the invention consists in a novel combination of parts and details of construction shown on the accompanying drawings which 30 form a material part of this disclosure and which are finally pointed out in the appended claims.

In the drawings:

Fig. 1 is a plan view of a mop embodying 35 the invention.

Fig. 2, is a sectional side elevation on line 2—2 of Fig. 1.

Fig. 3, is a plan view of my mop frame 40 from which the swatch is removed, showing the mop frame partly disconnected from its holder.

Fig. 4, is an enlarged detail plan on line 4—4 of Fig. 2 showing the engagement of 45 the curved frame ends with the holder bearing.

Fig. 5, is a sectional elevation on line 5—5 of Fig. 4.

Fig. 6 is an enlarged face view of the end 50 of 20a in the direction of the arrow of Fig. 3.

In the drawings, 10 is a helical coil of wire,

having an open wound portion 10a and a close wound portion 10b of smaller diameter. The open wound portion 10a forms a threaded socket for a mop stick 13, the bottom of which leans against the first turn of 10b which 55 forms a stop therefor. The coil portion 10b holds two flat plates 11 which lie against each other and have each a wide part 11c and a narrow part 11b. Integral with each plate, outside of coil 10b a semicylindrical bearing 60 portion 11a is formed thereon which extends transversely to the coil axis to both sides thereof.

The bearing plates 11 are driven into coil 10b by force so that the coil is expanded 65 by 11c and the plates locked in the coil by the contraction of those of its turns which lie against 11b.

The resiliency of the coil-turns 10b permit 70 however when force is exerted between the two semicylindrical bearing parts 11a some slight separation thereof so that these parts may clamp an object between them. This mop holder forms the subject matter of my copending application for Letters Patent, entitled "Holders for dusters and the like", filed 75 May 8, 1928, Ser. No. 275,985, and the present invention has for its object the carrying forward of the same inventive concept, by providing novel means which cooperate with 80 the above mentioned holder.

The cylindrical bearing 11a holds at opposite ends rotatably mounted therein the end portions 20a of a looped bar 20 which is preferably made of spring steel, of a diameter to 85 fit loosely into bearing 11a. The loop formed by bar 20 is of "heart" shape, its forward portion is triangular, rounded at its apex, the open side which is attached to bearing 11a is bent inwardly towards the center of the 90 triangle at 20b, with a second bend forming the pivot end portions 20a which are curved as illustrated by Fig. 4.

The mop swatch consists of mop threads 95 21 which are held together by a tubular fabric binding 22, stitched at 22a to form a sheath which is slipped over one pivot end 20a of the mop frame and all around the same to the opposite end 20a covering the frame 20 completely. The resiliency of the frame 20 100

permits ends $20a$ to be sprung so far apart that bearing $11a$ may be placed between the two ends $20a$ as shown in Fig. 3 and to be inserted into that bearing. While the diameter of rod 20 is slightly less than the interior diameter of bearing $11a$ the curvature of pivots $20a$ makes the extreme point $20c$ which is shaped to form a spur and middle part $20d$ lean tightly against the inner surface of bearing $11a$, and as the transverse distance between these extreme points is slightly greater than the diameter of the bearing $11a$ the frame ends will, when rotated, drive the bearing plates 11 slightly apart. When spurs $20c$ enter the slot $11e$ between the bearing plates $11a$ these plates are partly released of their strain and will close so far together that they hold the mop frame in this position, until force is exerted by means of the leverage afforded by the frame loop to spread the bearing plates apart by rotating frame 20 . At $11d$ the bearing plates $11a$ are provided with notches which slightly engage the spurs $20c$ so that some force must be applied to move pivots longitudinally out of bearing $11a$. Generally it is desirable to bend the spurs $20c$ so that the frame 20 is arrested to lie in the plane of the mop stick axis, but by bending pivots $20a$ in a different plane than that of frame 20 the latter may be arrested at any other angle relative to the mop stick axis. The resiliency of the frame 20 and the friction of curved pivots $20a$ against bearing walls $11a$ hold the mop firmly connected to its holder at any angle with the mop stick axis.

This mop offers various advantages against similar devices which use a swatch of similar construction. Most of such devices have an open gap at some place of the loop-frame which is bridged by the sheath. It is a frequent occurrence in the use of such mops that a narrow vertical rod, as for instance the leg of a heating radiator is caught in the gap between the ends of the mop frame and the sheath is loosened thereby from the frame. The present invention prevents this occurrence but does not prevent the removal of the sheath from the mop frame for cleaning or renewal. Another advantage gained by my invention is the increased stability inherent in a closed frame and particularly the feature that the mop frame and sheath may be removed together from the holder without the use of tools, which permits to have several mops attachable to the same holder; one for instance to be used with oil and the other with water.

The frictional engagement of the curved pivots with the mop holder bearing, which is partly produced by the spring action of the holder and partly by the curvature and resiliency of the pivots, prevents the mop from swinging on its pivots when such swinging is not desired and the locking action of the

bearing jaws holds the mop firmly in the plane of its handle, which is very desirable for storing and shipping. In addition to all these advantages the construction of the whole mop and frame is so simple that it may be manufactured and sold at a very reasonable price. 70

While I have described the preferred form of my invention it shall be understood that such modifications may be made in the arrangement of parts and in the construction of minor details as may come within the scope of the appended claims. 75

What I claim as new and desire to secure by Letters Patent is: 80

1. A mop head comprising a handle engaging portion having a transverse bearing thereon consisting of a pair of oppositely curved plates and means to hold said plates in juxtaposition, a looped mop supporting frame having opposed resilient end portions adapted to slide longitudinally into said bearing to be rotatably mounted therein and means on said end portions co-operating with means on said plates to hold said frame detachably locked to said bearing. 85

2. A mop head comprising a handle engaging portion having a transverse bearing thereon consisting of a pair of oppositely curved plates forming a slot between their abutting edges parallel to the bearing axis, a looped mop supporting frame having opposed end portions forming separate pivots mounted in said bearing and spurs on said pivots adapted to enter the slot between said plates to arrest their rotation in said bearing and to hold said frame in fixed position. 90

3. A mop comprising a handle engaging portion having a transverse bearing thereon, consisting of a pair of oppositely curved plates, a looped frame having integral opposed end portions spaced from each other and adapted to enter said bearing from opposite ends, the loop of said frame providing resilient means to hold said end portions within said bearing and resilient means on said handle engaging portion to press said plates yieldingly against said end portions. 95

4. A mop head comprising a handle engaging portion having a transverse cylindrical bearing thereon, a looped mop supporting frame having opposed end portions rotatably mounted in said bearing, said end portions being longitudinally slidably into and out of said bearing and humps on said end portions pressing against the cylindrical inside of said bearing causing friction therewith to restrict movement of said end portions in said bearing. 100

Signed at Brooklyn, in the county of Kings and State of New York, this 17th day of November A. D. 1928. 105

HARRY HERTZBERG.
